UNITED STATES PATENT OFFICE

134,884

DESIGN FOR A PHOTOGRAPHIC MOUNT

Harold Engelstein, New York, N. Y.

Application December 4, 1942, Serial No. 108,954

Term of patent 3½ years

To all whom it may concern:

Be it known that I, Harold Engelstein, a citizen of the United States and residing in Manhattan, in the city, county, and State of New York, have invented a new, original, and ornamental Design for a Photographic Mount, of which the following is a specification, reference being had to the accompanying drawing, forming part thereof, wherein

Fig. 1 is a perspective side view of a photo-

graphic mount showing my new design, in the unpasted state.

Fig. 2 is a perspective side view of a photographic mount, showing my new design, with the edges pasted and finished.

I claim:

The ornamental design for a photographic mount, substantially as shown and described.

HAROLD ENGELSTEIN.
